ATTORNEY

UNITED STATES PATENT OFFICE.

ARTHUR K. POMEROY, OF WASHINGTON, DISTRICT OF COLUMBIA, ASSIGNOR TO
FRANK HIGGINS, OF ROCKVILLE, MARYLAND, TRUSTEE FOR THE SHARE-
HOLDERS OF THE INTERNATIONAL SHOE HEEL CORPORATION.

CUSHION HEEL.

Application filed January 28, 1921, Serial No. 440,693. Renewed December 22, 1921. Serial No. 524,294.

To all whom it may concern:

Be it known that I, ARTHUR K. POMEROY, a citizen of the United States, residing at Washington, in the District of Columbia, 5 have invented new and useful Improvements in Cushion Heels, of which the following is a specification.

This invention relates to cushion or shock absorber heels and it consists in the novel 10 features hereinafter described and claimed.

An object of the invention is to provide 15 a cushion or shock absorber heel with means for easily and quickly assembling the heel and then attaching the same to a heel seat 15 of a shoe in a manner to efficiently hold the heel in position thereon.

Another object of the invention is to improve 20 the structure of a heel, whereby maximum resiliency is attained, and at the same time the structure is preserved in a simple 20 and durable form.

With these objects in view, the heel structure includes a cushion insert provided at 25 its upper side with a recess adapted to receive a metallic plate. Alining openings are 30 in the cushion insert and a leather lift which also forms a part of the heel. Securing devices are passed transversely through the alining openings of the leather lift, the insert, 35 and the plate and secure the said lift, the insert and the plate in position upon the heel of the shoe. The said insert is provided with a series of openings, and a lift 40 is secured to the lower face of the insert and closes the said openings at one end and the heel seat of the shoe closes the upper end 45 of said openings, whereby plenums of air are retained in the openings. A top lift is applied to the last mentioned lift in the usual manner.

In the accompanying drawings:

Figure 1 is a sectional view of a portion 45 of a shoe with the cushion heel applied.

Figure 2 is a top plan view of the cushion 45 insert of the heel, the metallic plate also being shown and a portion thereof is broken away.

Figure 3 is an under plan view of the same.

Figure 4 is an under plan view of the 50 metallic plate, which fits in the recess of the cushion insert.

Figure 5 is a detail sectional view of thus when the cushion heel is applied to

the heel structure cut on the line 5—5 of Figure 3. 55

The cushion or shock absorber heel, as shown in Figure 1, comprises an insert 1 of elastic material, preferably rubber. The said insert is provided at its upper side with a continuous recess 2, shown in Figure 2, 60 the outer edge of which is spaced approximately at a uniform distance from the edge of the said insert. A metallic plate 4 is adapted to snugly fit in the recess 2. The insert 1 is provided at spaced intervals with 65 openings 7, as shown in Figure 1 of the drawings. A metallic plate 4 fits snugly in the recess 2, and the upper surface of the said plate is flush with, or may be set below the upper surface of the insert 1, as 70 best shown in Figures 1 and 5 of the drawings. The plate 4 is provided with a series of openings 5 and openings 6.

The insert 1 is also provided at the bottom of the recess 2 with a series of transverse pockets 3, which align with another series of transverse openings or pockets designated by the numeral 3' in the leather lift 11. The said leather lift 11 is applied to the under side of the insert 1, and closes 80 the lower ends of the openings 7 in the insert 1, and the heel seat 10 of the shoe closes the upper ends of said openings for the retention of plenums of air within said openings. Studs 12 pass transversely 85 through the openings 6 of the plate 4, the insert 1 and the leather lift 11 and clinch at the base of the leather lift 11, and the said nails are provided at their upper ends with suitable heads as shown at 8, to engage 90 against the upper surface of the plate 4 in a manner similar to the corresponding devices shown in my Patent No. 1,162,709.

The recesses 2, in the insert 1, can be deepened sufficiently to allow space between 95 nail head 8 and the base of the heel seat to admit of longitudinal action of nail 12. In the latter case a buffer with holes therein to accommodate heads 8 can be placed between the steel plate and the base of the heel seat, 100 thereby providing an opening for heads 8, without cutting the same into the heel seat. Said buffer can be made of leather, leather-board of fiber and shaped to conform to the outer and inner lines of the steel plate, and 105 thus when the cushion heel is applied to

the shoe, and the shoe is in use, the nails 12 may have slight longitudinal movement through the plate 4, when the insert 1 is compressed. Top lifts 15 are applied to the 5 lower side of the lift 11 and are secured in position thereon by means of nails or slugs 16, which pass transversely through the said lifts. Nails 17 pass transversely through the lifts 11 and through the insert 1, and through holes 6 in the plate 4 and then into the heel seat 10 of the shoe and are clinched in said heel seat as best shown in Figure 5 of the drawings.

To assemble the cushion or shock absorber heel, the plate 4 is positioned in the recess 2 15 of the insert 1, (see Figure 2) and studs 12 are driven through the plate 4, the cushion insert 1 and leather lift 11, and clinch in lift 11. The assembled heel is then placed on 20 the heel seat and nails 11 are driven through the lift 11, insert 1, until the heads strike plate 4, the nails passing through the heel seat and clinched against the metallic base of the last. The lifts 15 are then applied to 25 the lift 11 and secured by means of the nails or slugs 16, in the usual manner. If desired, an implement of a suitable design (not shown), may be provided for driving all of the studs 12 home at the same operation. 30 Inasmuch as the said implement forms no part of the present invention, it is not shown or otherwise described.

From the above description taken in conjunction with the accompanying drawings, it 35 will be seen that a cushion or shock absorber heel of simple and durable structure is provided, and that the parts mutually cooperate with each other to render the heel elastic by the use of the resilient insert 1, and the combined plenum openings thereof. Also the 40

structure is of such nature that it may be easily and quickly applied to a heel seat of a shoe.

It is obvious that those skilled in the art 45 may vary the details of construction and arrangement of parts without departing from the spirit of my invention and therefore I do not wish to be limited to such features except as may be required by the 50 claims.

Having thus described the invention, what is claimed as new, is:—

1. A cushion heel comprising an insert of 55 resilient material provided at its upper side with a recess, a metallic plate located in the recess, said insert being provided at the bottom of the recess with pockets, a lift applied to the lower side of the insert, securing devices passing transversely through the plate at the ends of the pockets in the insert 60 and adapted to enter the heel seat of a shoe, and studs passing through the lift, the insert and the plate.

2. A cushion heel comprising an insert of 65 elastic material provided at its upper side with a recess having at the bottom of the recess pockets, a metallic plate adapted to fit snugly in the recess and bridge the pockets therein whereby plenums of air are confined to said pockets, a lift applied to the lower side of the insert, securing devices 70 passing transversely through the plate at the ends of the pockets in the insert and adapted to enter the heel seat of a shoe, and studs passing transversely through the lift, the insert and the plate, and provided at their upper ends with enlarged heads which engage over the upper surface of the plate.

In testimony whereof I affix my signature.

ARTHUR K. POMEROY.
